UNITED STATES PATENT OFFICE.

FRANK H. MERRILL, OF BOUND BROOK, NEW JERSEY, ASSIGNOR TO THE MERRILL MANUFACTURING COMPANY, OF NEW JERSEY.

APPARATUS FOR RAISING WATER OR OTHER LIQUIDS.

SPECIFICATION forming part of Letters Patent No. 558,880, dated April 21, 1896.

Application filed August 10, 1894. Renewed March 12, 1896. Serial No. 582,983. (No model.)

To all whom it may concern:

Be it known that I, FRANK H. MERRILL, a citizen of the United States, and a resident of Bound Brook, in the county of Somerset 5 and State of New Jersey, have invented certain new and useful Improvements in Apparatus for Raising Water or other Liquids, of which the following is a specification.

Pneumatic pumps have been constructed 10 by me in which the valve controlling the supply of compressed air was shoved backward as well as forward by the compressed air passing through the water-compartment. I have discovered a new mode of operation in which 15 the valve is shoved in one direction by the compressed air passing through the water-compartment, but is shoved in the other direction by air received from the compressed-air-supply pipe without going through the water- 20 compartment. This new mode of operation enables me to greatly simplify the apparatus employed, and thus materially improve it in the matter of durability, cost, and unattended 25 operation.

I will set forth in the following specification two forms in which this new mode of operation may be embodied. In one form the continuance of the exhaust is limited by 30 the closing of a vent by the action of a float and in the other form by the regulation or size of a vent so timed as to continue the exhaust long enough for the water-compartment to have time to fill.

Figure 1 of the accompanying drawings is 35 an elevation of an apparatus with the various inclosures sectioned to show the interior construction. Figs. 2 and 3 are details of the same. Fig. 4 is an elevation of another form of apparatus with the inclosures sectioned. 40 Fig. 5 is a plan view of the same.

I will first describe the form shown in Fig. 1. *a* is the shell of the water-compartment, which consists of a single casting open at top and bottom. *b* and *b'* are a base-plate and a 45 hollow pedestal cast in one piece. The plate covers the lower opening of the shell *a* and is provided with a central opening closed by the valve *b²*. *c* is a cast plate closing the top opening of the shell *a*. To the plate *c* are 50 connected the various parts hereinafter referred to. *d* is a cast chamber provided with

bottom and side openings for pipe connections. *e* is a casting of the form shown, on top of which is placed the cast plate *f*. All of these castings are simple in construction, 55 and therefore do not add largely to the cost of the apparatus. The remainder of the apparatus is very largely made up of piping and unions or valves, which are already to be had upon the market, and therefore do not add 60 much to the cost, the result being that the whole apparatus, while efficient, may be very cheaply constructed.

g is a water-delivery pipe extending from its mouth near the bottom of the compartment *a* upward through the plate *c* and thence to the point of delivery. It contains a check-valve at *g'* near (within thirty feet above) the compartment *a*.

h is a compressed-air-supply pipe leading 70 to a chamber *e'* at the bottom of the casting *e*.

d' is a pipe connecting the middle of the chamber *d* with the top of a vertical cylinder *e²* in the upper end of the casting *e*.

e³ is a smaller cylinder in the casting *e* intermediate the chamber *e'* and a chamber *e⁴*, which cylinder contains side perforations *e⁵*, leading into a passage *e⁶*. The cylinder *e³* opens at the top into the chamber *e⁴* and at the bottom into the chamber *e'*. The cylinder *e²* opens at the bottom into the chamber *e⁴*. The chamber *e⁴* is provided with a side opening *e⁷* into the open air. 75

i is a piston in the cylinder *e²*, connected by a rod *i'* with a smaller piston *i²* in the cylinder *e³*. 85

j is a pipe connecting the passage *e⁶* with the top of the compartment *a*, passing through the plate *c*.

k is a pipe extending from the bottom of 90 the chamber *d* through the plate *c* into the top of the compartment *a*, where it is provided with a branch pipe *k'*.

k² is an upwardly-opening check-valve in the pipe *k* below the branch pipe *k'*. In the 95 lower end of the pipe *k* is a downwardly-opening valve *l*, to which is connected a lever *l'*, from which is suspended a closed float *l²*.

m is an upwardly-opening valve at the end of the branch pipe *k'*, upon which is supported a bell-shaped float *m'*. This float *m'* preferably occupies a position in a narrow up-

ward extension or neck of the compartment *a*, as shown in Fig. 1.

The operation may be described as follows: Suppose, in Fig. 1, the compartment *a* to be full of water and compressed air to be supplied through the pipe *h*. This compressed air will pass through the cylinder *e*³, perforations *e*⁵, and pipe *j* into the top of compartment *a* and will force the water therein out of the delivery-pipe. When the water-level is lowered sufficiently, the float *l*² will drop and open the valve *l*, whereupon the compressed air will pass through the pipe *k* into the chamber *d* and thence through the pipe *d*¹ into the top of the cylinder *e*². The compressed air being now above the piston *i* and beneath the piston *i*² will, by reason of the greater size of the former piston, force both of them downward into the position shown in Fig. 2. In this position the piston *i*², acting as a valve, cuts off the supply of compressed air from the perforations *e*⁵ and opens an exhaust from the pipe *j* through the perforations *e*⁵, the cylinder *e*³, the chamber *e*⁴, and the opening *e*⁷. The pressure being thus removed from the compartment *a*, the check-valves *g*¹ and *k*² will close and the valve *b*² will open to admit the water in which the apparatus is immersed. As this water rises in the compartment *a* it will lift the float *l*², so as to close the valve *l*, and when it reaches the top of the compartment will begin to lift the float *m*¹, so as to open the valve *m* very slightly. This action connects the compressed air contained in the top of the cylinder *e*² and the chamber *d* and the pipes *d*¹ and *k* with the interior of the float *m*¹, causing that float to jump upward and open the valve *m* wide, thus quickly removing the pressure from the top of the piston *i* and permitting the compressed air acting on the bottom of the piston *i*² to shove the pistons into the position shown in Fig. 1, whereupon the whole operation is repeated.

I will now describe the form shown in Figs. 4 and 5, using, so far as feasible, the same letters to indicate corresponding parts.

a is the shell of the water-compartment, which consists of a single casting open at top and bottom.

b and *b*¹ are a base-plate and a hollow pedestal cast in one piece. The plate covers the lower opening of the shell *a* and is provided with openings closed by the valves *b*² *b*³.

c is a cast plate closing the top opening of the shell *a*. To the plate *c* are connected the various parts hereinafter referred to.

f is a cast structure containing the chamber *d*, provided with a bottom opening into the cylinder *e*² and a side opening into passage *d*².

e is a casting of the form shown, on top of which is placed the cast structure *f*.

g is a water-delivery pipe extending from its mouth near the bottom of compartment *a* upward through the plate *c* and thence to the point of delivery. It contains a check-valve

at *g*¹ near (within thirty feet above) the compartment *a*.

h is a compressed-air-supply pipe leading to a chamber *e*¹ at the bottom of the casting *e*.

*e*³ is a smaller cylinder in the casting *e* intermediate the chamber *e*¹ and a chamber *e*⁴, which cylinder contains side perforations *e*⁵, leading into a passage *e*⁶. The cylinder *e*³ opens at the top into the chamber *e*⁴ and at the bottom into the chamber *e*¹. The cylinder *e*² opens at the bottom into chamber *e*⁴ and at the top into chamber *d*. The chamber *e*⁴ is provided with a large side opening *e*⁷ into the open air.

i is a piston in the cylinder *e*², connected by a rod *i*¹ with a smaller piston *i*² in the cylinder *e*³.

j is a pipe connecting the passage *e*⁶ with the top of the compartment *a*, passing through the plate *c*.

k is a pipe extending from the passage *d*¹ through the plate *c* into the top of compartment *a*, where it is provided with a downwardly-opening valve corresponding with the valve *l* in Fig. 3, to which is connected a lever *l*¹, from which is suspended a closed float *l*².

*k*² is an upwardly-opening check-valve in the pipe *k*.

o is a vent connecting the passage *d*² with the open air, the size of which vent is controlled by a set-screw valve *o*¹.

The operation of the form shown in Figs. 4 and 5 may be described as follows: Suppose in Fig. 4 the compartment *a* to be full of water and compressed air to be supplied through the pipe *h*. This compressed air will pass through cylinder *e*³, perforations *e*⁵, and pipe *j* into the top of compartment *a* and will force the water therein out of the delivery-pipe *g*. When the water-level is lowered sufficiently, the float *l*² will drop and open the valve at *l*, whereupon the compressed air will pass through the pipe *k* into the chamber *d* into the top of the cylinder *e*². The compressed air being now above the piston *i* and beneath the piston *i*² will, by reason of the size of the former piston, force both of them downward, thus cutting off the supply of compressed air from the perforations *e*⁵ and opening an exhaust from the pipe *j* through the perforations *e*⁵, the cylinder *e*³, the chamber *e*⁴, and the opening *e*⁷. The pressure being thus removed from the compartment *a*, the check-valves *g*¹ and *k*² will close and the valves *b*² and *b*³ will open to admit the water in which the compartment is immersed to the extent of just submerging the compartment *a*. As this water rises in the compartment *a* it will lift the float *l*², so as to close the valve *l*. This action cuts off the chamber *d* from any compressed air entering the water-compartment, but entraps sufficient air in the chamber *d* to prevent the upward movement of the cylinder *i* until that air has been exhausted. The size of the vent *o* is so regulated by the set-screw valve *o*¹ that the time required for exhausting the air from the

chamber *d* will be practically sufficient to permit the compartment *a* to be filled with water. When this condition of things is reached, the compressed air in passage *h* being unopposed by pressure in the chamber *d* will force the pistons *i* and *i*² back into the position shown in Fig. 4, when the operation already described will be repeated.

In both forms of apparatus the valve *i*² at 10 one end of its stroke connects the passage *j* with the pressure-passage *h*; but when at the opposite end of its stroke it connects the passage *j* with the exhaust-passage *e*¹. The valve is held in the latter or exhaust position 15 by the air entrapped in the chamber *d* and connected passages by the valve in the passage *k* remaining closed while the pressure from the pipe *h* is cut off from the compartment *a*. In both forms as soon as this entrapped air is vented sufficiently (in one case 20 past the float-controlled valve *m* and in the other case past the set-screw-controlled valve *o*) the compressed air in the supply-passage *h* reasserts itself and forces the valve *i*² back 25 into its first or pressure position.

I do not wish to be understood as limited to any specific form of apparatus.

The piston *i*² is to be considered, broadly, as a movable member, located in the supply-pipe and connected with the valve mechanism, whereby the valve mechanism is impelled by the pressure in the supply-pipe, or, in other words, by the pressure of the air in the pipe leading to the water-compartment 35 in contradistinction to the pressure of air which has passed through the water-compartment, or one division thereof in case it is in two parts, as in a double-acting pump.

I claim—

40 1. In a liquid-raising apparatus, in combination, a liquid-compartment, a liquid-delivery passage as *g*, a compressed-gas-supply pipe as *h*, *j* to said liquid-compartment, a gas-exit passage as *k*, a valve as *l* in the same, a float operated by the liquid in the compartment and controlling said valve, valve mechanism to cut off the gas supply containing a piston, as *i*², which moves in antagonism to the supply-current of gas as the same is cut off, and means whereby the pressure of gas in said exit-passage is exerted to produce said movement of said piston; substantially as described.

2. In a liquid-raising apparatus, in combination, a liquid-compartment, a liquid-delivery passage, a compressed-gas-supply passage, a pressure-controlling valve, a passage whereby the compressed gas from said liquid-compartment is applied to the movement of said valve in one direction, a float-operated valve whereby said passage is controlled, a check-valve in said passage whereby the compressed gas applied to the movement of said valve is entrapped and a vent through which said entrapped air escapes to permit said pressure-regulating valve to be moved in the opposite direction, substantially as described.

3. In a liquid-raising apparatus containing a liquid-compartment, a liquid-delivery passage as *g*, a compressed-gas-supply passage as *h*, *j*, a pressure-controlling valve as *i*², means for operating the same by the pressure in a gas-exit passage, a gas-exit passage as *k* with which the compartment communicates and which is provided with an exhaust-passage as *k*', in combination with said parts the following parts whereby the timing of the pressure and exhaust in said gas-exit pipe is controlled, viz: a valve as *l* controlling the opening from the compartment into said passage *k*, a float in the compartment controlling said valve *l*, a valve, as *m*, controlling said exhaust-passage *k*', a float in the said compartment controlling said valve *m*, said floats being located respectively at or near the bottom and top of said compartment, substantially as described.

4. In a liquid-raising apparatus in combination, a liquid-compartment, a liquid-delivery passage, a compressed-gas-supply passage, a pressure-controlling valve in the same, a float operated by the liquid at its lower level in the liquid-compartment, another float operated by the liquid at its upper level in the liquid-compartment, a piston operating 95 to close said pressure-regulating valve, a cylinder for said piston, a pipe connecting said cylinder with the water-compartment, a valve in said pipe controlled by said first-named float whereby pressure is admitted to said cylinder and a valve controlled by said last-named float whereby pressure is relieved from said cylinder, substantially as described.

5. In a liquid-raising apparatus in combination, a liquid-compartment, a liquid-delivery passage, a compressed-gas-supply passage, a pressure-controlling valve in the same, a float operated by the liquid at its lower level in the liquid-compartment, another float operated by the liquid at its upper level in the liquid-compartment, means whereby said pressure-controlling valve is controlled in one direction by pressure from the liquid-compartment, a pipe conducting said pressure from the liquid-compartment to said means, a branch from said pipe, check-valves in said pipe and the branch therefrom, a valve in said pipe controlled by said first-named float and a valve in said branch controlled by said second-named float, substantially as described.

6. As a means for controlling the pressure-controlling valve in a pneumatic pump in combination with said valve and the liquid-compartment of the pump, a piston operated to close said valve, a cylinder for said piston, a pipe communicating the pressure from the liquid-compartment to said cylinder, an exhaust-valve in said pipe and a bell-shaped float in the liquid-compartment connected with said valve and surrounding the valve-opening whereby as the rise of liquid raises said float the exhaust of the pressure into said float facilitates its opening of the valve, substantially as described.

7. In a liquid-raising apparatus operated by compressed gas in combination, a liquid-compartment, a pressure-supply passage *h*, a passage *j* extending between the same and the liquid-compartment, an exhaust-passage, a valve whereby said passage *j* is alternately connected with the passage *h* and with the exhaust-passage, a piston connected with said valve, a cylinder for said piston, a passage connecting said cylinder with said liquid-compartment, a valve in said last-named passage whereby the air in said cylinder is entrapped upon the removal of pressure from the liquid-compartment, a vent for the escape of the entrapped air and means whereby said vent is controlled, substantially as described.

8. In a liquid-raising apparatus operated by compressed gas, in combination, a liquid-compartment, a cylinder *e*, a pressure-passage *h* connected with one end of said cylinder, an exhaust-passage, a passage *j* connecting said cylinder with the water-compartment, a piston-valve in said cylinder whereby said passage *j* may be connected with the pressure or exhaust, a piston *i* of larger diameter than said piston-valve connected therewith, a cylinder for said piston *i*, a passage leading from said liquid-compartment to said last-named cylinder, a valve in said last-named passage whereby the air is entrapped in said last-named cylinder, a vent for the escape of the entrapped air and means whereby said vent is controlled, substantially as described.

9. In a liquid-raising apparatus operated by compressed gas, in combination with the liquid-compartment and a compressed-gas-supply pipe and a water-delivery pipe, the following parts as a means of controlling pressure in the water-compartment, viz: two connected pistons of different areas arranged substantially as described, whereby the smaller is subjected to the pressure from the supply-pipe, a valved passage whereby communication is opened between the liquid-compartment and said larger piston when the liquid-compartment is under pressure and closed when the liquid-compartment is under exhaust, a vent through which the pressure upon said larger piston is relieved and means for controlling said vent, substantially as described.

10. In a liquid-raising apparatus operated by compressed gas, in combination, a liquid-compartment, a pressure-supply passage *h*, a passage *j* extending between the same and the liquid-compartment, an exhaust-passage, a valve whereby said passage *j* is alternately

connected with the pressure-passage *h* and with the exhaust-passage, a piston connected with said valve, a cylinder for said piston, a chamber *d*, passages *d'* and *k* connecting said chamber respectively with said cylinder and said liquid-compartment, a valve in the passage *k* whereby the air in the chamber *d* is entrapped upon the removal of pressure from the liquid-compartment, a vent for the escape of the entrapped air and means whereby said vent is controlled, substantially as described.

11. In a liquid-raising apparatus, in combination, a liquid-compartment, a liquid-delivery pipe, a compressed-gas-supply pipe, a valve-chamber connected therewith, a pipe connecting said valve-chamber with the liquid-compartment, a valve in said valve-chamber by the movement of which in antagonism to the compressed-gas supply, the liquid-compartment is cut off from said supply and connected with an exhaust, a gas-passage from said liquid-compartment, a valve in the same, a float operated by the liquid in the liquid-compartment and controlling said last-named valve, power-differentiating mechanism whereby the pressure of gas in said last-named passage is multiplied and transmitted to move said first-named valve in antagonism to the gas supply and a check-valve whereby the compressed air is entrapped in contact with said power-differentiating mechanism, substantially as described.

12. In a liquid-raising apparatus, in combination, a liquid-compartment, a liquid-delivery pipe, a compressed-gas-supply pipe, a pressure-controlling valve closing the same by moving antagonistically to the pressure therein, an exhaust connected with the liquid-compartment upon the cutting off of such pressure, power-differentiating mechanism connected with said pressure-controlling valve, a gas-passage from said liquid-compartment to said power-differentiating mechanism, a valve in said gas-passage, a float operated by the liquid in the liquid-compartment whereby said last-named valve is controlled, a check-valve whereby said gas is entrapped at said power-differentiating mechanism and a vent through which said gas escapes from said trap, substantially as described.

Signed at Bound Brook, in the county of Somerset and State of New Jersey, this 7th day of August, A. D. 1894.

FRANK H. MERRILL.
